(57) **CLAIM**

The ornamental design for a wireless vehicle charger, as shown and described.

DESCRIPTION

2. Wireless vehicle charger

2.1: Front perspective view

2.2: Back perspective view

2.3: Front

2.4: Back

2.5: Top

2.6: Bottom

2.7: Left

2.8: Right

2.9: Reference view showing the state in use

Design 2: The article is a wireless vehicle charger for charging a battery of electric movement bodies, such as a vehicle or hull, from outside; the features shown in broken lines depict environmental subject matter only and form no part of the claimed design; the lines having alternating long and short segments define bounds of the claimed design and form no part thereof.
